UNITED STATES PATENT OFFICE.

EDWARD ERICKSON, OF LYNN, MASSACHUSETTS, ASSIGNOR TO VICTOR SHOE MACHINERY CO., OF BOSTON, MASSACHUSETTS, A CORPORATION OF MASSACHUSETTS.

MOVABLE GUARD FOR SEWING-MACHINES.

1,149,353.

Specification of Letters Patent.

Patented Aug. 10, 1915.

Application filed July 20, 1914. Serial No. 852,102.

To all whom it may concern:

Be it known that I, EDWARD ERICKSON, a subject of the King of Sweden, and a resident of Lynn, in the county of Essex and 5 State of Massachusetts, have invented certain new and useful Improvements in Mov- able Guards for Sewing-Machines, of which the following is a specification.

This invention relates to sole sewing ma- 10 chines and particularly to means for pro- tecting the work from being injured or soiled during the operation of the machine, and has for its object the provision of means for protecting the work from the operating 15 parts of the machine.

This invention consists in providing the awl supporting member with a guard adapt- ed to be moved laterally therewith in contact with the front face of the work support 20 during the feeding operation.

The invention further consists in certain 25 novel features of construction and arrangement of parts which will be fully understood by reference to the description of the draw- ings and to the claims hereinafter given.

Of the drawings: Figure 1 represents a 30 front view of a machine embodying the prin- ciples of the present invention, and Fig. 2 represents a vertical section of the same, looking to the right of Fig. 1.

Similar characters designate like parts throughout the figures of the drawings.

The invention is illustrated as applied to 35 a sole-sewing machine similar to that shown and described in application filed by Law- rence E. Johnson and myself, May 19, 1913, Ser. No. 768,671, to which reference may be made for the complete operation of the ma- chine.

In the drawings 20 is the base of the ma- 40 chine adapted to be secured to a column and having the end frames 21 and 22 provided with bearings for a revoluble shaft 23. The revoluble shaft 23 has the driving wheel 24 secured to one end thereof, while to its op- 45 posite end is keyed the cam disk 25. Inter- posed between the side frames 21 and 22 and keyed to the shaft 23 is the cam disk 27. The cam disks 25 and 27 are adapted 50 to operate various mechanisms necessary for the proper operation of the machine, all of which have been fully illustrated and de- scribed in the application 768,671, hereinbe- fore referred to. As many of these mecha-

nisms form no part of the present invention 55 they are not herein described.

To the inner side of the side frame 21 is secured the work support 28 which may be of any well-known construction. The side frame 21 has also formed upon its inner face 60 a race 30 for the shuttle 31 which is driven in any well-known manner. The frame 22 is provided with two bearings in which recip- rocate two parallel studs or pins 60—61 mounted upon a movable frame 62. This 65 frame has pivoted to the lower end thereof at 63 an oscillating slotted lever 64, the lower end of which is provided with a roller 65 extending into a cam path 66 in the per- 70 ipery of the cam disk 27. In the slot 67 of the lever 64 is a fulcrum block 68 pivot- ally mounted in a forked member 69 having a shank 70 extending through a straight slot 71 in the frame 22, and also through a slot 72 in a hand lever 73 pivoted at 74 to the 75 end frame 22. It is obvious that when the cam disk 27 rotates, the cam path 66 thereof will operate upon the roller 65 to actuate the lever 64 about its fulcrum, thereby mov- 80 ing the frame 62 a given distance, this dis- tance depending upon the position of the fulcrum pin 77. The inclination of the slot 71 conforms to that of the lever 64 to permit the free movement of the forked member 69 lengthwise of the lever 64 without binding 85 thereon. By means of the handle 63 the position of the fulcrum block 68 may be changed at will to secure any desired de- gree of speed. The frame 62 has mounted thereon the shaft 80 carrying the needle 90 guide 83. Rotatable about the axis of the shaft 80 is a needle support 85 carrying the needle 84. The needle support 85 has a gear segment 86 formed thereon through which oscillatory movement may be imparted to 95 the needle and the awl 91 also secured to said needle support 85. The machine is also provided with the looper 126 operated by suitable mechanisms which form no part of the present invention. The needle and awl 100 support move laterally with the frame 62 and when the awl is in the work the said frame 62 will be fed relatively to the work support 28, the length of feed being deter- 105 mined by the handle 73. When the needle leaves the work the frame 62 is returned to its normal position before the awl again moves forward to pierce the work.

Secured to the frame 62 is a guard 100 which is curved outwardly and in front of the work support 28 as is clearly indicated in Figs. 1 and 2 of the drawings. When the frame 62 is moved laterally to feed the work the guard 100 is interposed between the work and the work support and moves with the latter, thereby preventing the work from being injured by contact with the work support and also keeping the work out of the path of the operating parts of the machine adjacent thereto such as the looper 126, the awl 91, and the needle 84.

This guard constructed as shown and described not only prevents the work from being injured or soiled but also prevents the work from assuming such a position as to interfere with the operation of the machine. By providing a guard of this character and attaching it to the work feeding devices the feeding of the work is greatly facilitated, as during the feeding operation the work would be free from frictional contact with any stationary part of the machine.

It is believed that the operation and many advantages of a guard of the character described will be fully apparent without further description.

Having thus described my invention, I claim:

1. In a sole-sewing machine, the combina-

tion of a work support; needle and awl actuating mechanism; a member movable horizontally to feed the work on said support; and a guard secured to said member and movable therewith to protect the work during the operation of the machine.

2. In a sole-sewing machine, the combination of a work support; needle and awl actuating mechanism; a member movable horizontally to feed the work on said support; and a guard secured to said member and movable therewith in contact with the front face of the work support to protect the work during the operation of the machine.

3. In a sole-sewing machine, the combination of a work support; needle and awl actuating mechanism; a member supporting the awl and movable horizontally to feed the work on said support while the awl is positioned in said work; and a guard secured to said member and movable therewith to protect the work during the operation of the machine.

Signed by me at 4 Post Office Sq., Boston, Mass., this 10th day of July, 1914.

EDWARD ERICKSON.
